UNITED STATES PATENT OFFICE

DEWEY H. BITNEY, OF ALBION, MICHIGAN, ASSIGNOR TO UNION STEEL PRODUCTS COMPANY, OF ALBION, MICHIGAN

STRUCTURAL UNIT

Application filed January 11, 1932. Serial No. 585,824.

The main objects of this invention are:

First, to provide a structural unit by means of which a plurality of reinforcing elements may be effectively supported in definite relation to each other.

Second, to provide a reinforce element supporting structural unit which may be quickly applied to a beam, joist studding or the like and the reinforce elements quickly engaged therewith and supported thereby in parallel and transverse relation.

Objects pertaining to details and economies of my invention will definitely appear from the description to follow. The invention is defined in the claims.

A structure which embodies the features of my invention is clearly illustrated in the accompanying drawing, in which:

Fig. 1 is a fragmentary perspective view of my improved structural element applied to an I-beam, the beam being indicated by dotted lines.

Fig. 2 is a detail view partially in section on line 2—2 of Fig. 3.

Fig. 3 is a fragmentary side elevation.

Fig. 4 is an enlarged fragmentary view partially in section on line 4—4 of Fig. 3.

In the embodiment of my invention illustrated in the accompanying drawing my improved structural unit comprises a longitudinal rod 1 which in practice is of substantial length and is formed of springable material. To this rod I secure in fixed spaced relation a plurality of supports 2 provided with hooks 3 at one end adapted to be engaged with opposed flanges 4 of an I-beam 5 or other structural element. The supports 2 are formed of wire and are preferably welded to the longitudinal member so that they become, in effect, a fixed part thereof.

To the upwardly projecting ends of these support members 2 I secure a plurality of reinforce holders 6. These reinforce holders are disposed transversely of the longitudinal rod and transversely of the supports, and are provided with upturned ends 7 at one end which coact with the ends 8 of the supports 50 in providing upwardly facing seats 9 for

reinforce bars. The other ends of these supports have spring arms 10 which are spaced from and preferably overhang the longitudinal rod to engage a reinforce member 16 arranged on the rod, see Fig. 3. The ends of the arms 10 are turned inwardly to provide reinforce engaging hooks 15.

The reinforce bars may be quickly snapped under these holders, the hooks 15 springing over the rods and snapping down behind the same, effectively retaining them in place. This permits very rapid engagement of the rods with the supports.

The longitudinal rods are in the embodiment illustrated also provided with U-shaped reinforce holders 11 disposed transversely of the longitudinal rod intermediate the support members 2 and fixedly secured to the longitudinal rod by one arm, preferably by welding as indicated in Fig. 4. The other arms 12 of these holders are free to swing to permit engagement of reinforce bars 14 with the holders, the arms 12 terminating in inturned hooks 13 which engage the reinforce bars and effectively retain them in position.

Normally the longitudinal rods are straight but they may be sprung to engage alternate hooks 3 with opposite edges of the structural member, the hooks facing in opposite directions as illustrated in Fig. 1. There is sufficient resilience in the rod 1 to permit this manipulation and to hold the supports in engagement with the beam, joist or other element.

The holders described permit very rapid engagement of the reinforce members, both with the arms 10 and in the holders 11, and after these have been engaged the bars 9, 14 and 16, may be arranged in the upwardly facing seats. The upwardly facing seats described are adapted either to receive a reinforce bar or a screed bar, as may be desired.

I have illustrated and described my improvements in an embodiment which is highly satisfactory. I have not attempted to illustrate or describe certain modifica-

tions and adaptations for particular uses as it is believed this disclosure will enable those skilled in the art to embody or adapt my improvements as may be desired.

5 Having thus described my invention what I claim as new and desire to secure by Letters Patent is:

1. A structural unit comprising a longitudinal rod of springable material, a plurality of support engaging members fixedly secured to said rod in spaced relation to project at each side thereof and having hooks at one end engageable with the flange of a beam or the like structural element, the hooks of adjacent support engaging members being disposed to engage opposite edges of the supporting element, reinforce holders fixedly secured to the other ends of said support members transversely thereof 20 and transversely of said rod and having spring arms at one end disposed in spaced relation to the rod and terminating in in-turned reinforce engaging hooks, the other ends of said reinforce holder members being directed upwardly and coacting with the ends of the support members to provide reinforce seats, and U-shaped clips disposed transversely of said longitudinal rod intermediate its said support members, one arm thereof being fixedly secured to the rod, the other arm being free and springable to receive a reinforcing element and having its end directed inwardly to provide a reinforce 25 engaging member.
- 35 2. A structural unit comprising a longitudinal rod of springable material, a plurality of support engaging members fixedly secured to said rod in spaced relation to project at each side thereof and having hooks 40 at one end engageable with the flange of a beam or like structural element, the hooks of adjacent support engaging members being disposed to engage opposite edges of the supporting element, reinforce holders 45 fixedly secured to the other ends of said support members transversely thereof and transversely of said rod and having spring arms at one end disposed in spaced relation to the rod and terminating in in-turned reinforce 50 force engaging hooks, the other ends of said reinforce holder members being directed upwardly and coacting with the ends of the support members to provide reinforce seats.
- 55 3. A structural unit comprising a longitudinal rod of springable material, a plurality of support engaging members fixedly secured to said rod in spaced relation to project at each side thereof and having hooks 60 at one end engageable with the flange of a beam or like structural element, the hooks of adjacent support engaging members being disposed to engage opposite edges of the supporting element, reinforce holders 65 fixedly secured to the other ends of said

support members and having spring arms disposed in spaced relation to the rod and terminating in in-turned reinforce engaging hooks, and U-shaped clips disposed transversely of said longitudinal rod intermediate its said upper members, one arm thereof being fixedly secured to the rod, the other arm being free and springable to receive a reinforcing element and having its end directed inwardly to provide a reinforce 70 engaging member.

4. A structural unit comprising a longitudinal rod of springable material, a plurality of support engaging members fixedly secured to said rod in spaced relation to project at each side thereof and having hooks at one end engageable with the flange of a beam or like structural element, the hooks of adjacent support engaging members being disposed to engage opposite edges of the supporting element, and reinforce holders fixedly secured to the other ends of said support members and having spring arms disposed in spaced relation to the rod and terminating in in-turned reinforce 75 engaging hooks.

5. A structural unit comprising a longitudinal rod, a plurality of support engaging members fixedly secured to said rod in spaced relation to project at each side thereof, reinforce holders fixedly secured to said supporting members transversely thereof and transversely of said rod and having spring arms at one end disposed in spaced relation to the rod and coacting therewith to retain a reinforce element, the other arms of said reinforce holder members being disposed to coact with the support members to provide reinforce seats, and U-shaped reinforce 95 holders disposed transversely of said longitudinal rod intermediate of said support members, one arm of said holders being secured to the rod and the other being free and springable to receive a reinforce 100 element.

6. A structural unit comprising a longitudinal rod, a plurality of support engaging members fixedly secured to said rod in spaced relation to project at each side thereof, reinforce holders fixedly secured to said supporting members and having spring arms at one end disposed in spaced relation to the rod and coacting therewith to retain a reinforce element, and U-shaped reinforce 115 holders disposed transversely of said longitudinal rod intermediate of said support members, one arm of said holders being secured to the rod and the other being free and springable to receive a reinforce element.

7. A structural unit comprising a longitudinal rod, a plurality of support engaging members fixedly secured to said rod in spaced relation to project at each side thereof, and reinforce holders fixedly secured to said 120

supporting members transversely thereof and transversely of said rod and having spring arms at one end disposed in spaced relation to the rod and coacting therewith to 5 retain a reinforce element, the other arms of said reinforce holder members being disposed to coact with the support members to provide reinforce seats.

8. A structural unit comprising a longitudinal rod, a plurality of support engaging members fixedly secured to said rod in spaced relation to project at each side thereof, and reinforce holders fixedly secured to said supporting members and having 15 spring arms at one end disposed in spaced relation to the rod and coacting therewith to retain a reinforce element.

9. A structural unit comprising a longitudinal rod, a plurality of support engaging members fixedly secured to said rod in spaced relation to project at each side thereof, and reinforce holders fixedly secured to said supporting members transversely thereof and transversely of said rod 20 and having spring arms at one end disposed in overhanging spaced relation to the rod and coacting therewith to retain a reinforce element, said spring arms terminating in inwardly directed hooks.

10. A structural unit comprising a longitudinal rod, a plurality of support engaging members fixedly secured to said rod in spaced relation to project at each side thereof, and reinforce holders fixedly secured to said supporting members transversely thereof and transversely of said rod and having spring arms at one end disposed in overhanging spaced relation to the 25 rod and coacting therewith to retain a reinforce element, said spring arms terminating in inwardly directed hooks.

11. A structural unit comprising a longitudinal rod, a plurality of support engaging members fixedly secured to said rod in spaced relation to project at each side thereof, and reinforce holders fixedly secured to said supporting members transversely thereof and transversely of said rod and having spring arms at one end disposed in overhanging spaced relation to the rod and coacting therewith to retain a reinforce element.

In witness whereof I have hereunto set my hand.

DEWEY H. BITNEY.
